HOOD FOR COLLECTING GASES

Paul Pierrat and Eugene Colombe, Paris, France,
assignors to La Cellophane, a French companyApplication January 4, 1950, Serial No. 136,673
In France January 13, 1949

3 Claims. (Cl. 18—8)

1

This invention relates to a hood for collecting gases from treating vessels and particularly to hoods to collect gases from open top tanks used in viscose spinning or casting processes.

An object is to provide a device of this type which is sealable to the tank and which may be raised when necessary to afford access to the tank for service purposes.

Another object is to provide means to remove concentrated gases and recover usable constituents therefrom.

Another object is to provide a device of the above type having improved details of construction and novel features of operation.

Various other objects and advantages will be apparent as the nature of the invention is more fully disclosed.

In the manufacture of thread, films, etc. of regenerated cellulose from viscose, use is commonly made of acid baths which give rise to the formation of carbon disulfide and a certain amount of hydrogen sulfide. The liberation of these gases into the atmosphere involves serious disadvantages from the point of view of health, apart from any objectionable odors, and means have frequently been proposed for mitigating these odors and for counteracting the harmfulness of spinning gases. Attempts have also been made to collect the gaseous sulfur compounds contained in spinning gases, and in particular to collect and recover carbon disulfide in the spinning of rayon and staple fibers.

The present invention provides a device of simple construction and exceptionally efficacious in the collection of gases liberated in viscose treating plants, particularly in plants manufacturing films or spinning and treating continuously staple fiber or rayon, and permits convenient recovery of the carbon disulfide contained in these gases.

The device consists essentially of a movable hood having at least one suction duct and having one or more gas inlets. The hood is connected by a hydraulic seal to close the treating vessel where the gases to be collected are liberated.

The hood may be raised by a hydraulic lift. It may also be mechanically counterbalanced for manual operation.

Because of the rapid liberation of the vapors, the degassing vessel, e. g. for a film gel in process of fixation, is provided with a heating means, for example steam injection nozzles.

The invention will be better understood in terms of the accompanying drawings, wherein:

Fig. 1 is a longitudinal section of the first two tanks of a machine for the manufacture of regenerated cellulose films showing the hood pursuant to the invention.

Fig. 2 is a transverse section taken on the line 2—2 of Fig. 1;

Fig. 3 is a longitudinal section similar to Fig. 1 showing a further embodiment of the invention; and

2

Fig. 4 is a transverse section taken on the line 4—4 of Fig. 3.

In accordance with the example of embodiment shown in Figs. 1 and 2, the numeral 1 designates the first tank in a process for manufacturing regenerated cellulose films, e. g. of the type described in U. S. Patent No. 1,601,289, dated September 28th, 1926. In this tank the viscose leaving the slit 30 of the casting hopper 31 is coagulated in the bath 32 to form a wide strip 33 of gel. This strip is passed around guides 34 and 35, then over rollers 36 and 37 into a second tank 2 containing an acid bath, and then through following tanks containing water and in some instances heated to 85° C. to 95° C. by any means, e. g. by nozzles for injection of steam. The tank 2 may be divided into a pair of treating vessels by a partition 38. The tank 2 and the following tanks contain series of rollers or other guiding means 4 and 5, conveying the strip in a zig-zag path through the respective baths. The tank 2 is provided with slits 39 and 40 through which the web passes into and out of a tank.

The upper edge of the tank 2, throughout its periphery, carries a trough 6 filled with a liquid, such as water, to form a hydraulic seal with the lower edge of a hood 7 covering the said tank. This hood is suspended by at least one hydraulic lifting device 8, fixed at its upper end to a beam 41 or other support. This device is raised hydraulically or otherwise, to raise the hood sufficiently to afford access to the vessel 2 for starting the plant or for other purposes.

The hood 7 has an internal stack 9 surrounding a ventilating duct 10, with suction ports 11 at the base and a damper 12 (Fig. 1) or other means of controlling the suction.

The gases collected in the duct 10 are carried to a recovery condenser. This device is particularly suitable for the recovery of carbon disulfide by simple condensation.

The operation is as follows: After the machine has been started and the strip of gel passed around the rollers or guides 4 and 5, the hood 7 is lowered until its lower edge enters the trough 6, where the water or other liquid will form a hydraulic seal. Suction is then applied to the duct 10 by operating the damper 12. If the gel breaks or if the machine is stopped, the suction is first shut off, the hood is raised by means of the lifting device 8, and the machine can be restarted. Note that the suction may be left on while the hood is open to ensure a constant supply of fresh air, thus facilitating the operations of the workmen, in which case the suction may be reinforced by another and more powerful blower if desired. The tank may be provided with gas inlets 42 for purging purposes. The hood may be counterbalanced by weights 43 suspended on collar 44 passing over pulleys 45.

Figs. 3 and 4 show a variant by means of which two different suctions can be obtained, according

to whether the hood is lowered or raised, the suction being stronger for the latter position of the hood.

In this embodiment the lower edge of the hood 13 rests in a hydraulic seal 15 on the tank 14, and has a suction duct 16 as in the first embodiment. There is also a plate 17 secured underneath the hood and resting on supports 18. The tank also has a second outlet 19 connected to a condenser C.

The plate 17, throughout its periphery, is provided with a trough 20 filled with water or other liquid to receive a flange 21 attached to the hood 13 and forming a tight seal when the hood is lowered over the tank 14.

When the hood 13 and the two hydraulic seals 15 and 20 are closed, suction takes place through the stack 19, and the hydraulic seal 20 prevents any intake of gas into the duct 16. When the hood 13 rises, the suction by way of the stack 19 is shut off, and the duct 16 takes up the noxious gases, the hydraulic seal 20 being then open. The hood has a neck 22 sliding on the duct 16, which is fixed in this case.

With the use of the devices just described, the required ventilation and conditioning of spinning plants can be greatly reduced. All the noxious gases are eliminated and working conditions are much improved in a hygienic sense, with a much lower expenditure of heat energy for air conditioning. Moreover, the noxious gases are collected in a concentrated form, and their treatment either by combustion or for recovery is facilitated.

Another advantage due to the presence of the hood is that the evaporation of the bath is much reduced, with resulting diminution of heat losses from this cause, while at the same time the vapors cannot spread through the plant. It is sometimes desirable, in general, to provide hoods for the subsequent tanks containing hot baths, even without suction, in order to reduce loss of heat energy through vaporization, and to avoid their unrestricted diffusion.

To avoid an accidental dropping of the hood during work, any standard safety device may be provided.

It may be desirable to flush the interior of the hood or hoods with an inert gas supplied through the inlets 42 after each operation, e. g. with nitrogen, to avoid a mixture of air with gases rich in carbon disulfide, with possible danger of explosion.

In the case of the machine shown in Figs. 1 and 2, the degassing may of course be completed in one or more other tanks with hoods similar to that described, or in any other suitable arrangement, with immersion of the gel in hot water. The ventilating ducts of all the tanks may be joined in a central collector. The hoods in addition to sealing the tanks against the escape of fumes permit the gases to be collected in concentrated form suitable for recovery when the hoods are lowered. When the hoods are raised the suction duct 19 leading to the recovery apparatus is closed and the dilute gases are removed through the duct 16. In this way the dilute gases are prevented from entering the recovery apparatus. Naturally the invention is in no way restricted to the embodiment shown and described.

What is claimed is:

1. In a viscose spinning or casting machine, means forming viscose into a continuous flat web, side and end walls forming an open top tank containing a treating liquid, means feeding said

web through said treating liquid, a movable hood closing the top of said tank, a hydraulic seal extending around the top of said walls, with the lower edge of said hood forming a part of said seal, a stationary suction duct passing vertically through said head and having ports communicating with the interior of said tank, a hydraulic lifting device connected to said hood to lift the hood for access to said tank, said hood having a member having a sliding fit around said duct and movable with the hood to maintain a gas-tight connection, and means counterbalancing said hood for lifting.

2. In a viscose spinning or casting machine, means forming viscose into a continuous flat web, side and end walls forming an open top tank containing a treating liquid, means feeding said web through said treating liquid, a movable hood closing the top of said tank, a hydraulic seal extending around the top of said walls, with the lower edge of said hood forming a part of said seal, a stationary suction duct passing vertically through said hood and having ports communicating with the interior of said tank, a lifting device connected to said hood to lift the hood for access to said tank, means to close said ports comprising a stationary bottom plate having a hydraulic seal extending around the area of said ports and a flange on said hood forming a part of said last hydraulic seal when said hood is in lowered position, a second suction duct communicating with said tank and gas-collecting apparatus connected to said last duct to receive gases when said first duct is closed by the lowering of said hood.

3. In a viscose spinning or casting machine, means forming viscose into a continuous flat web, side and end walls forming an open top tank containing a treating liquid, means feeding said web through said treating liquid, a movable hood closing the top of said tank, a hydraulic seal extending around the top of said walls, with the lower edge of said hood forming a part of said seal, a stationary suction duct passing vertically through said head and having ports communicating with the interior of said tank, a lifting device connected to said hood to lift the hood for access to said tank, means to close said ports comprising a stationary bottom plate having a hydraulic seal extending around the area of said ports and a flange on said hood forming a part of said last hydraulic seal when said hood is in lowered position, a second suction duct communicating with said tank and gas-collecting apparatus connected to said last duct to receive gases when said first duct is closed by the lowering of said hood, and means controlling the suction of the respective ducts.
